FLOOR WAXING DEVICE

James Gordon, Chicago, Ill.

Application February 2, 1946, Serial No. 645,104

9 Claims. (Cl. 91—37)

1

This invention relates to a floor waxing device more particularly for waxing and polishing floors and the like in domestic establishments for example.

The invention aims to provide, among other objects, a relatively light-weight portable device for this purpose which may be manually operated without the need for any other power means and in which the application of the wax to the floor may be optionally controlled by the operator while the device is in motion and with a minimum of effort on the part of the operator, while simultaneously, the device continues to polish the floor to which the wax is continuously or successively applied as desired.

The machine of the present invention provides a remarkably simple and inexpensive device for this purpose, which may be produced in quantities at relatively low cost and which may be handled by the householder in much the same way as the old-fashioned carpet sweeper.

These and other objects and advantages will be apparent from the following describing, taken together with the accompanying drawings, of an illustrative device embodying the present invention, and in which drawings—

Figure 1 is a plan view with parts broken away for purposes of description;

Figure 2 is a somewhat side elevational view but shown principally in section taken on the line 2—2 of Figure 1; and

Figure 3 is a detailed view showing one of the bearings for journaling the shaft of the applicator brush and being a section taken on the line 3—3 of Figure 2.

Referring in detail to the illustrative construction shown in the drawings, the device in general comprises a main frame 10, an auxiliary frame 11, and an operating handle 12. The main frame 10 is mobile as by being carried in this instance by two pairs of wheels, one pair being indicated by the numerals 13 and 14, and the other pair by the numerals 15 and 16. The front pair of wheels 13 and 14 mount the front axle 17, which is journalled, preferably by ball bearings as at 18, in the side walls 19 of the main frame. Similarly, the rear pair of wheels 15 and 16 mount the rear axle 20, which is journalled as by ball bearings 21 also in the main frame side walls 19.

Forward of the front pair of wheels 13 and 14,

5 the main frame carries a polishing roller 22 which is faced as at 23 with a soft material such as felt, and which is adapted at all times to contact the floor such as 24 upon which the device may be operating. The polishing roller 22 is carried on an axle 25, which is journalled in a cylindrical bearing block 26 at each end of the axle, as by a ball bearing 27. Each cylindrical block 26 is rigid with a bearing stem 28 which extends upwardly and threadedly through a knurled thumb nut 29 which is rotatable above the top wall 31 of the frame 10. The bearing stem 28 passes freely through a grommet 32 fixed in an opening 30 in the main wall 31. The grommet is secured on the 10 under face of the wall 31 at 33. Thus, since the bearing stem 28 is threaded as at 34 to mate with corresponding threads 35 in the bore of the nut 29, rotation of the nut will raise or lower the axle 25 with respect to the frame 10. A conical coil 15 spring 36, through which the bearing stem 28 passes, bears at its upper larger end against the under face of the frame wall 31 and at its lower smaller end against the cylindrical bearing block 26 and resiliently retains the axle 25 in vertically 20 elongated slots 37 in the frame side walls 19. Thus is provided a floating resilient suspension 25 for the polishing roller. This resilient arrangement accommodates irregularities in the floor 24, such as the edge of linoleum, or a threshold, and 30 permits the polishing roller 22 to rise in that case with respect to the frame 10 without the entire device being raised. The thumb nut 29 permits the polishing roller to be lowered to accommodate for wear therein, the spring 36 following the 35 axle downwardly and maintaining a downward pressure on the axle, and this pressure is then adjustable.

40 A spur gear 38 on the inner face of the front wheel 14 meshes with another spur gear 39 on the axle 25 to rotate the polishing roller 22 at all times when the device is in motion. The gear 38 is larger than the gear 39 so that the polishing roller will rotate faster than the wheels 13 and 14, and in the opposite direction, as indicated by the arrows A for the wheel and B for the polishing roller.

45 The auxiliary frame 11 is pivoted as by bracket extensions 40 thereof on the front main frame axle 17, for upward and downward movements 50 with respect to the main frame under the in-

fluence of the operating handle 12 as desired by the operator and for the purpose next described.

The auxiliary frame 11 carries a rotary applicator brush 41. The drum 42 which is carried on an axle 43 of the brush is journalled at each end in a cylindrical bearing block 44 which is rigid with a bearing stem 45 which passes freely through a grommet 46 in the upper wall 11a of the auxiliary frame. The upper end of the bearing stem 45 is threaded as at 47 to pass threadedly through the knurled thumb nut 48 on the upper side of the frame wall 11a. The coil spring 49, through which the bearing stem 45 passes, presses at its upper end against the under face of the frame wall face 11a and at its lower end against the cylindrical bearing block 44. Since the outer ends of the axle 43 pass through vertically elongated slots 50 in the auxiliary frame side walls 51, the axle 43 may move limitedly and resiliently upward or downward with respect to the auxiliary frame to accommodate for irregularities in the floor 24, similarly to the polishing roller 22, when the rotary applicator brush is caused to engage the floor as next described.

The rear wheel 16 carries a spur gear 52 upon its inner face which meshes with another smaller spur gear 53 fixed on the axle 43 of the rotary applicator brush when the auxiliary frame is lowered from the position shown in full lines in Figure 2 to a position shown in dotted lines in Figure 2 as at 54. Thus at the latter time, the applicator brush 41 is caused to rotate at a speed faster than the rotation of the wheels 13, 14, 15 and 16, and in the opposite direction as indicated by the arrows A for the wheel and B for the rotary brush.

The rotary applicator brush 41 is adapted to contact a cake of a polishing material such as solidified wax 55 which is received in a compartment 56 formed in the hollow upper part 57 of the auxiliary frame 11. A door 58 hinged as at 59 on the upper side of the auxiliary frame provides access to the compartment 56, the knob 60 being provided for manipulation of the door or cover plate 58. The compartment 56 is open at the lower end so that it communicates with the brush 41, and thus the wax cake 55 rests in part by gravity on and in contact with the bristles of the brush 41 at all times both when the brush is stationary in elevated position as shown in full lines in Figure 2, and also when the brush is lowered to contact the floor as indicated in dotted lines and as already alluded to.

To assist the action of gravity in holding the wax in contact with the brush, I provide a resilient plate 61 which is carried by a pair of conical coil springs 62, one at each end of the plate, the smaller upper ends of which are anchored on pins 63 fixed on the upper wall 64 of the frame part 57 and within the compartment 56. The plate 61 has a shank 65 which extends outwardly of and plays vertically in a narrow elongated slot 66 in the rear under face 67 of the frame part 57. Threaded on the shank 65 is a knurled thumb nut 68 which is adapted to clamp the washer 69 against the wall 67, and thus secure the plate 61 in any desired position in the slot 66, as for example, to retract the plate 61 when a cake of wax is being inserted. When the nut 68 is loosened, the plate 61 is free to follow the wax bar or cake 55 downwardly and maintain a pressure on the cake urging it into contact with the rotary brush 41.

The handle 12 may have a reduced lower part,

70 by which it is fitted snugly into the tubular extension 71 arranged centrally of and fixed to the upper wall 64 of the auxiliary frame part 57, a screw bolt 72 securing the handle therein.

5 In order to limit swinging movement of the auxiliary frame 11 to a point where it will not rub against the rear axle 20 but will still be free to engage the floor, the auxiliary frame carries a lug 73 projecting from one of its sides, as here shown in the upper part of Figure 1, to engage the upper wall 31 of the main frame 10 and act as a stop member.

15 By providing two of the adjustment nuts 29, one at each side of the main frame, and also two adjustment nuts 48, one at each side of the auxiliary frame, an inclination transversely of the frame may be given to either or both of the polishing roller 22 and applicator brush 41, to accommodate further irregularities which there 20 may be in the floor being worked upon.

25 As best seen in Figure 3, which shows details of the resilient floating suspension for the axle of the applicator brush (and which is similar to that for the polishing roller), the roller bearings 25 27 may be inserted into the bearing block 44, for example, by providing the axle 43 with a reduced end 74. After the axle is located in the bearing block 44 and the balls 27 also located in their race 75, one-half of which is in the axle 43, the 30 sleeve 76, in the inner end of which is formed the other half of the race 75, is then secured over the reduced end 74 of the axle and riveted to be rigid therewith as at 77. In this instance, the gear 53 may be carried rigid with sleeve 76. 35 Between the nuts 48 the upper wall 11a of the auxiliary frame 11 is desirably arched as at 11b to conform to the rotary brush 41.

40 In order to enhance the traction of the wheels 13, 14, 15, and 16, they are desirably provided with rubber tires 80 having embossed treads 81.

45 So constructed and arranged the operator may readily propel the device along the floor by pushing it through the medium of the handle 12, while at the same time steering the device as desired. 50 Either continuously or at optional intervals, the operator may lower the auxiliary frame 11 with respect to the main frame 10 on its pivot as described, to cause the brush 41 to engage the floor. When the auxiliary frame is thus lowered, the gears 52 and 53 will engage and the brush 41 will be rotated to transfer particles of wax from the cake 55 to the floor 24. During the entire 55 movement of the device, the polishing roller 22 continues to contact the floor, and to work the wax into the floor surface.

The invention is not intended to be limited to details of construction shown for illustrative purposes, and such changes may be made as fall within the scope of the following claims without departing therefrom.

The invention having been described, what is here claimed is:

1. In a floor waxing device of the class described, the combination with a mobile frame, of a hollow part of said frame having a compartment for receiving a cake of solidified wax, a rotary applicator brush axled in the frame communicating with said compartment, a spring pressed follower plate arranged to press said cake into engagement with said rotary brush, a door for said compartment, and means for holding the plate temporarily in retracted position.

2. In a floor waxing device of the class described, the combination with a mobile frame, of a hollow part of said frame having a compartment

ment for receiving a cake of solidified wax, a rotary applicator member axled in the frame communicating with said compartment, a spring pressed follower plate arranged to press said cake into engagement with said rotary member, and means including a shank on said plate, a slot in said frame receiving said shank outwardly therethrough, and a thumb nut screwed on said shank, for holding the plate temporarily in retracted position.

3. In a floor waxing device, the combination with a main frame, of pairs of wheels for the frame arranged front to rear thereof, an auxiliary frame carried by the main frame and pivoted for up and down movement thereon, between the front and rear wheels, a rotary member axled in the auxiliary frame, a wax supply container carried by the auxiliary frame adjacent said rotary member, a handle rigid with said auxiliary frame for causing up and down movements thereof, means for rotating said rotary member by rotation of one of said wheels and engaged when the auxiliary frame is lowered by said handle but disengaged when the auxiliary frame is raised by said handle, whereby upon propulsion of said device and lowering of the auxiliary frame by the handle the rotary member may be caused to rotate in the opposite direction to the rotation of said wheel to receive wax on its periphery from the container and to transmit said wax to a floor or the like, another rotary member carried by the main frame, and means for rotating the last mentioned rotating member upon rotation of one of said wheels, whereby said last mentioned rotary member may provide a polishing action on the floor.

4. In a floor waxing device, the combination with a main frame, of pairs of wheels for the frame arranged front to rear thereof, an auxiliary frame carried by the main frame and pivoted for up and down movement thereon, a rotary brush axled in the auxiliary frame, a wax supply container carried by the auxiliary frame adjacent said brush, a handle rigid with said auxiliary frame for causing up and down movements thereof, and interengaging gears rigid with said rotary brush and one of said wheels respectively and engaged when the auxiliary frame is lowered by said handle but disengaged when the auxiliary frame is raised by said handle, whereby upon propulsion of the device and lowering of the auxiliary frame by the handle the rotary brush may be caused to rotate in the opposite direction to the rotation of said wheel to receive wax on its periphery from the container and to transmit said wax to a floor or the like.

5. In a floor waxing device, the combination with a frame having front and rear wheels, of an auxiliary frame pivoted on the main frame between the wheels for up and down movement thereon, a rotary floor engaging member journaled in the auxiliary frame, a handle carried by the auxiliary frame rigidly therewith, gears rigid with the rotary member and one of said rear wheels respectively adapted to be brought into mesh when the handle is lowered and arranged to rotate the member, a wax supply container carried by the auxiliary frame adjacent said rotary member, another rotary floor engaging member carried by the main frame, and meshing gears rigid with the last mentioned rotary member and one of said front wheels respectively for rotating the said last mentioned rotary member.

6. In a floor waxing device, the combination with a main frame, of pairs of wheels for the

frame arranged front to rear thereof, an auxiliary frame pivoted on the main frame for up and down movement on the main frame, a rotary floor treating member axled in the auxiliary frame, a spur gear rigid with a rear wheel, a smaller spur gear rigid with the rotary floor treating member, said gears being engaged when the auxiliary frame is lowered to cause the floor treating member to rotate with rotation of the rear wheel but out of engagement when the auxiliary frame is raised, another rotary floor treating member adjacent the front wheels, a gear rigid therewith, a gear rigid with a front wheel member engaging said gear rigid with the last mentioned rotary member, a resilient suspension for said floor treating members on said auxiliary frame and said main frame respectively, a handle carried rigidly by said auxiliary frame, and a wax supply container carried by the auxiliary frame adjacent the first-mentioned rotary member.

7. In a floor waxing device, the combination with a main frame, of pairs of wheels for the frame arranged front to rear thereof, an auxiliary frame pivoted on the front wheel axle for up and down movement on the main frame, a rotary floor treating member axled in the auxiliary frame, a wax supply container carried by the auxiliary frame adjacent said rotary member, a spur gear rigid with a rear wheel, a smaller spur gear rigid with the rotary floor treating member, said gears being engaged when the auxiliary frame is lowered to cause the floor treating member to rotate with rotation of the rear wheel but out of engagement when the auxiliary frame is raised, a resilient floating suspension for said floor treating member on said auxiliary frame, and a handle carried rigidly by said auxiliary frame.

8. In a floor waxing device, the combination with a main frame, of pairs of wheels for the frame, an auxiliary frame carried by the main frame and pivoted for up and down movement thereon, a rotary floor treating member axled in the auxiliary frame, a wax supply container carried by the auxiliary frame adjacent said rotary member for holding a supply of wax in contact with said rotary member, a handle carried by said auxiliary frame for causing up and down movements thereof, and relatively rotatable means rigid with said rotary member and one of said wheels respectively and engaged when the auxiliary frame is lowered by said handle but disengaged when the auxiliary frame is raised by said handle, whereby upon propulsion of the device and lowering of the auxiliary frame by the handle the rotary member may be caused to rotate in the opposite direction to the rotation of said wheel to receive wax on its periphery from the container and to transmit said wax to a floor or the like.

9. In a floor waxing device, the combination with a main frame, of pairs of wheels for the frame arranged front to rear thereof, an auxiliary frame pivoted on the front wheel axle for up and down movement relative to the main frame, a rotary floor treating member axled in the auxiliary frame, a wax supply container carried by the auxiliary frame adjacent the rotary member in wax delivery relation thereto, a gear rigid with a rear wheel, a smaller gear rigid with the rotary member, said gears being engaged when the auxiliary frame is lowered to cause the member to rotate with rotation of the rear wheel, whereby on rotation of the member to transfer portions of said material to the rotary

member and from the rotary member to the floor.

JAMES GORDON.
